LELAND W. BIRCH, OF MANSFIELD, OHIO, ASSIGNOR TO THE OHIO BRASS COMPANY, OF MANSFIELD, OHIO, A CORPORATION OF NEW JERSEY

CATENARY HANGER

Application filed December 2, 1931. Serial No. 578,486.

My invention relates to a system of overhead support for conductors and hangers for use with such system.

The object of my invention is to provide a hanger and system which will prevent arcing between the hanger and support and thus eliminate burning.

My invention resides in the new and novel construction, combination and relation of the various parts herein described and shown in the drawing accompanying this specification.

In the drawing:

Fig. 1 is an end view of my invention.

Fig. 2 is a side or face view of Fig. 1.

Fig. 3 is a view similar to Fig. 1 with a trolley wire in position showing the normal relation of the trolley wire with respect to the hanger and its support.

Fig. 4 is a view similar to Fig. 3 but showing the hanger and trolley wire in a different relative position to the hanger support.

Fig. 5 is a schematic view of my system showing the relation between the hangers, their support and the trolley wire.

On most catenary systems of supporting the trolley wire the hanger between the trolley wire and the catenary cable is free to move vertically relative to the catenary cable as the current collector or a moving vehicle passes underneath the hangers.

Most hangers are provided with a loop at the upper end which passes around the catenary cable and provide a space between the catenary cable and the sides of the loop as the hanger moves vertically relative to the catenary cable.

With such construction the hanger will usually make and break contact with the catenary cable as it rises and falls.

As there is a flow of current between the catenary cable and trolley wire through the hanger, arcing and burning will be produced whenever the hanger breaks its contact with the catenary cable. To overcome this I have devised a clamp and arranged the same in a system whereby contact between the hanger and the catenary cable is maintained at the same time permitting freedom of movement vertically of the hanger relative to the catenary cable.

My invention may be applied to the various hangers now on the market.

Referring to the drawing I show a hanger comprising jaws 1 and 2 which may be moved relative to each other and which are held in a clamped position by means of the screw 3 provided with the central passage 4 and slot 5. The head of the screw is countersunk into the face of the jaw 2.

Projecting upwardly from between the jaws is a supporting member 6 with a loop 7 at the upper end. The loop is open at 8 so that the hanger may be applied to and taken from the messenger cable 9. The opening 8 is closed and maintained closed by a ring member 10 which may be easily positioned as shown in the drawing or displaced at will as the short member 11 of the loop is yieldable.

In order to grip the trolley wire 12 I provide a jaw with longitudinally disposed grips 13 and 14 but such grips are not so positioned opposite each other as to exactly register and it will be noted that the grip 14 is raised above the grip 13 such that when the jaws are applied to a trolley wire the position of the trolley wire will be as shown in Fig. 3 with respect to the vertical axis X—X of the hanger, that is, the vertical transverse axis A—A of the trolley wire will be angularly disposed with respect to the vertical axis X—X and the same is true of the transverse horizontal axis B—B of the trolley wire. It is apparent that holding the trolley wire in the manner just described will tend to place a torsion upon the trolley wire, that is, a tendency will always be present for the wire to seek the position as shown in Fig. 4.

My system comprises the trolley wire 12 and the catenary cable 9 as shown in Fig. 5 supported by the various hangers 20, 21, 22, 23 and 24 or any number as may be found desirable or necessary. The catenary cable may be suspended by supports 15. In placing the hangers 20 to 24 inclusive, etc., I employ hangers constructed as above described and shown in Figs. 1 to 4 but I alternate the hangers with respect to their faces as, for instance, hangers 20, 22, and 24 would be installed so as to throw the axis A—A in the same direc-

tion relative to the vertical plane of the trolley wire 12 and cable 9 and the hangers 21 and 23 will throw the axis A—A of the trolley wire 12 to the opposite side of the said vertical plane.

5 It must be apparent that alternating the hangers in this manner will put a definite torsion in the trolley wire tending to swing the axis A—A at each hanger to a vertical position and this will be in addition to the natural torsion set up through the weight of the trolley wire itself to assume a normal position.

10 The result of a system constructed with the hanger described will be to throw the loop of the hanger in the direction of the arrow shown in Figs. 3 and 4 and as the hanger rises and falls relative to the cable 9 the sides of the hanger loop will be thrown into and maintained in contact with the cable 9 thus preventing breaking contact between the hanger and cable and thereby eliminating arcing and burning.

15 I have found by tests that the grip 14 need not be raised above the grip 13 more than $\frac{1}{16}$ " to secure proper torsion in the trolley wire and that a side pressure of the hanger upon the cable 9 will amount to possibly 6 ounces. This would vary according to the 20 length of the hanger.

25 Tests have shown that the hanger so constructed and applied to a system as described will eliminate the burning and will not increase wear materially due to friction between the cable and hanger and, therefore, the life of the hanger and of the cable is 30 materially increased. It will be recognized that if burning takes place on the hanger it will also take place on the cable and while the hangers may be replaced, but at a considerable expense, the expense of replacing the cable will amount almost to a reconstruction 35 of the entire system.

40 It may seem that if a line were constructed of the ordinary type of hanger and that the contact between one hanger and the messenger cable should be broken that the shunting action of the other hangers would prevent any arcing but experiments have shown that 45 invariably arcing does take place when said contact is broken and the current may amount to only 10 to 20 amperes but this current has proved sufficient in combination with the 50 number of breaks which may take place in the course of time to bring disastrous effects 55 upon both the hanger and cable.

Having described my invention, I claim:—

55 1. A trolley wire clamp comprising an elongated supporting member, a pair of jaws secured thereto, each jaw having means co-operating with each other to engage and grip a trolley wire, the said means being displaced relative to each other in a vertical direction to hold the wire with its vertical transverse axis angularly disposed relative 60 to the vertical axis of the clamp and means

to draw the jaws into engagement with the wire.

2. A trolley wire clamp comprising an elongated supporting member having a pair of clamping jaws at the other end and means to move the jaws towards each other, each jaw having a ridge to engage opposite sides of a trolley wire, one ridge being out of vertical alignment with the other ridge to hold the wire in a twisted relation relative to the 75 vertical axis of the clamp.

3. A trolley wire clamp comprising an elongated supporting member having an elongated loop at one end to receive a supporting cable, the sides of the member within 80 the loop spaced apart a distance greater than the diameter of the cable, a pair of jaws secured to the other end of the member, means to move the jaws towards each other and hold them in engagement with a trolley wire 85 and against shifting relative to each other, each jaw having a means arranged to fit into the longitudinal groove of the trolley wire and hold the wire with its grooves rotated a predetermined amount about the longitudinal 90 axis of the wire.

4. An overhead system comprising a pair of supports, a cable supported by and between the supports, a trolley wire positioned below the cable and a plurality of hangers 95 supporting the wire from the cable and the hangers free to move relative to the cable in a vertical direction, the alternate hangers arranged to hold the trolley wire with a torsional twist therein in opposite directions 100 about its longitudinal axis, the said twist biased to hold the hangers in contact with the cable as they move relative to the cable.

5. A catenary trolley system comprising a messenger cable, a trolley conductor and a 105 plurality of spaced hangers for suspending the conductor from the cable in movable relation thereto, every other hanger gripping the conductor in such manner as to set up a torsional force therein and in opposite directions 110 about the longitudinal axis of the conductor.

6. A catenary trolley system comprising a messenger cable, a trolley conductor and a 115 plurality of spaced hangers for suspending the conductor from the cable, each hanger having its upper end movable relative to the cable in a vertical and transverse direction and its lower end gripping the conductor against relative movement therewith, each 120 alternate hanger secured to the conductor with its vertical axis angularly disposed to the vertical axis of the conductor in opposite lateral directions and the upper end of the hanger pressing constantly against the 125 cable.

7. A catenary trolley system comprising a messenger cable, a trolley conductor and a plurality of spaced hangers for suspending the conductor from the cable, the lower end 130

- of each hanger securely gripping the conductor and the upper end encircling the cable in movable relation thereto, the hangers secured to the conductor in such manner that the conductor tends to rotate the upper end of the hangers in a transverse plane to the axis of the conductor and the cable opposes such rotation whereby the hanger is pressed constantly in engagement with the cable as it moves relative to the cable.
8. A catenary trolley system comprising a messenger cable, a trolley conductor and a plurality of spaced hangers for suspending the conductor from the cable, the lower end of each hanger securely gripping the conductor and the upper end encircling the cable in movable relation thereto, the hangers secured to the conductor in such manner that the conductor tends to rotate the upper end of the hangers in a transverse plane to the axis of the conductor and the cable opposes such rotation whereby the hanger is pressed constantly in engagement with the cable as it moves relative to the cable, some hangers tending to rotate in one direction and others in the opposite direction.
9. A catenary trolley system comprising a messenger cable, a trolley conductor and a plurality of spaced hangers for suspending the conductor from the cable the lower end of the hangers securely attached to the conductor and the upper end attached thereto in movable relation, the relation of the hanger to the conductor being such that the hangers tend to rotate in a plane transverse to the longitudinal axis of the conductor, some hangers rotatable in one direction and other hangers in the opposite direction.
10. A hanger comprising an elongated support member having means at one end to receive loosely a messenger cable and having a conductor clamp at the other end securely attached to the support, jaws on the clamp to engage and grip the conductor and hold the hanger thereto in such relation to the conductor that the vertical axis of the hanger will be angularly disposed to the vertical axis of the conductor.

In testimony whereof I affix my signature.
LELAND W. BIRCH.
